UNITED STATES PATENT OFFICE.

ROBERT J. STOKES, OF TRENTON, NEW JERSEY, ASSIGNOR TO THERMOID RUBBER COMPANY, OF TRENTON, NEW JERSEY, A CORPORATION OF NEW JERSEY.

DESIGN FOR A VEHICLE-TIRE.

49,233.

Specification for Design.

Patented June 20, 1916.

Application filed May 3, 1916. Serial No. 95,280. Term of patent 14 years.

To all whom it may concern:

Be it known that I, ROBERT J. STOKES, a citizen of the United States, and a resident of Trenton, county of Mercer, State of New Jersey, have invented a certain new, original, and ornamental Design for a Vehicle-Tire, of which the following is a specification, reference being had to the accompany-

ing drawing, forming part thereof, in which the figure is a sectional perspective view of the vehicle-tire forming the subject of my new, original, and ornamental design.

I claim:—

The ornamental design for a vehicle tire, substantially as shown.

ROBERT J. STOKES.
